US0D1004643S

(12) **United States Design Patent** (10) **Patent No.:** **US D1,004,643 S**
(45) **Date of Patent:** **** Nov. 14, 2023**

(54) **CAN CRUSHER**

(71) Applicant: **Xiaojian Ma**, Yutai County (CN)

(72) Inventor: **Xiaojian Ma**, Yutai County (CN)

(**) Term: **15 Years**

(21) Appl. No.: **29/833,397**

(22) Filed: **Apr. 4, 2022**

(51) **LOC (14) Cl.** **15-09**

(52) **U.S. Cl.**

USPC **D15/123**

(58) **Field of Classification Search**

USPC D15/122, 123, 128, 141

(57) **CLAIM**

The ornamental design for a can crusher, as shown and described.

DESCRIPTION

FIG. 1 is a perspective view of a can crusher showing my new design;

FIG. 2 is another perspective view of the can crusher thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof; and,

FIG. 8 is a bottom plan view thereof.

The broken lines illustrate portions of the can crusher that form no part of the claimed design.

1 Claim, 8 Drawing Sheets
